TENTER CLIP

Filed Dec. 10, 1929

UNITED STATES PATENT OFFICE

WILLIAM A. STELLING, OF PROVIDENCE, RHODE ISLAND, ASSIGNOR TO THE TEXTILE FINISHING MACHINERY COMPANY, OF PROVIDENCE, RHODE ISLAND, A CORPORATION OF RHODE ISLAND

TENTER CLIP

Application filed December 10, 1929. Serial No. 413,037.

This invention relates to an improved construction of tenter clip; and has for its object to provide a clip of this character which is so constructed that the jaw is permitted to drop freely and quickly to bite the fabric when the edge of the fabric is withdrawn from beneath the jaw control member.

A further object of the invention is the provision of a jaw control member with a greatly elongated bearing sleeve on which it is pivotally hung to prolong the working life of the control member and also to reduce the cramping of the swinging movement of the control member due to action upon it of the travelling work on which it rests.

A still further object of the invention is to provide a plurality of feeler fingers so as to distribute the weight of the control member and the jaw upon the travelling goods so that the weight of these members is less likely to force the goods into the slots beneath these fingers, particularly when the goods are thin or delicate.

A still further object of this invention is to so construct the control member that a minimum amount of machine operations will be required for shaping and mounting the same on its bearing member.

With these and other objects in view, the invention consists of certain novel features of construction, as will be more fully described, and particularly pointed out in the appended claims.

In the drawings:

Fig. 1 is a sectional side elevation showing the control member as having its abrupt free end about ready to fall as the goods are being withdrawn from the fabric engaging surface of the member;

Fig. 2 shows the control member as having dropped free of the goods permitting the swinging jaw to fall and so positively bite the fabric;

Fig. 3 is a top view of my improved tenter clip showing the spaced supporting arms with an opening therein and operating mechanism mounted in these arms;

Fig. 4 is a perspective view of the control member with the elongated pivot pin bearing tube therein;

Fig. 5 is a section of the control member through this bearing tube;

Fig. 6 is a top view showing a plurality of spaced feeler fingers mounted on a single bearing member; and

Fig. 7 is a side view of these fingers shown in Figure 6.

It is found in the practical operation of tenter clips of the top lift balanced construction type of advantage to permit the swinging jaw to drop freely and quickly when the work is withdrawn from beneath the fabric engaging or feeling surface of the control member, so as to permit the jaw to better bite and grip the goods and so prevent slipping and injuring of the fabric as is the case in some instances when the dropping of the jaw is sluggish or retarded, and to accomplish this, I have formed the free swinging end of the control member on an abrupt angle relative to the surface supported by the fabric so that its guard edge will not touch the edge of the receding fabric to interfere with the free dropping of the control member, and the swinging of the jaw supported thereby in its movement to cooperate with the fixed jaw to bite and so positively secure the fabric against slipping and injury. Also it is found of advantage to provide the control member with a greatly elongated pivot bearing to reduce side sway and cramping of the control member due to action of the travelling fabric on which it rests; to accomplish which I have provided an elongated tubular bearing member

through which the bearing pin extends into the side arms; also it is found of advantage particularly when the finer fabrics are being acted upon to employ a plurality of spaced apart feeler fingers on the control member so as to distribute the weight and so prevent these finer fabrics from being forced into the slots in the lower jaw beneath the feeler fingers when passing thereover; and the following is a detailed description of the present embodiment of my invention and showing the preferred means by which each of these advantageous results may be accomplished.

With reference to the drawings, 10 designates the body of the tenter clip which is

connected in the usual way to the tenter chain by means of rivets extending through the opening 8 having hardened bushings 9 therein. The forward portion of this body is shaped to provide a fixed jaw 11 having a hard brass surface plate 34, and a pair of widely spaced arms 12 extend from the rear of the body to overlie this fixed jaw 11. The free overhanging end portions of the arms are pierced to receive the pivot pin 13 on which the swinging jaw 14 is hinged through its spaced eyes 15. This jaw 14 is provided with a pair of rearwardly extending arms 16 between which is mounted a roller 17. The swinging action of this jaw 14 is governed by the control or feeler member 18, which member is provided with an elongated tubular bearing 19, see Figures 4 and 5, that extends between the bearing arms 12, where it is pivotally supported by means of the pivot pin 20. This control member is L-shaped with an arm 21 which has a feeling or fabric engaging surface 22 on its lower edge and which is smoothly finished to ride upon and be supported by the surface of the work or fabric 23. The end 24 of this bearing surface is very abrupt in its formation.

The guard surface or edge 25 of this control member extends at substantially a right angle to the fabric engaging surface 22 thereof, whereby when the edge of the fabric is withdrawn beyond this point 24 the control member is permitted to drop freely without again coming in contact with the edge of the fabric. I have found, however, that the guard edge cannot be positioned at any substantially different angle than that which I have shown. This control member is also provided with a notch 26 for the reception of the roller 17 whereby a dropping movement of the control member also permits a free dropping movement of the jaw 14, which free movement of the jaw permits it to more quickly and securely grip, and bind the fabric or work 23 against the lower jaw thus more positively preventing slipping and possible tearing and injuring the fabric.

In some instances, where delicate fabrics are being acted upon, it is found of advantage 50 to replace the single feeler or control member with one having a plurality of spaced fabric engaging surfaces, which construction is herein illustrated in Figure 6, in which three spaced fingers 27 are illustrated, all as being mounted on or cast with a single elongated bearing tube 28 and supported in the bearings 29 on the pivot pin 20. By this construction, the weight of the control member and the jaw is distributed over the surface of the fabric and will not force the fabric into the slot or slots 32 to bind the same in its action.

The slot 32 for receiving the feeler member is positioned inwardly from the edge of the 65 clip, a greater distance than is usual in clips

of this type, and consequently less oil or lint will collect on the control member.

The back of the frame of the clip is provided with an opening 31 which is so located as to allow greater freedom of movement 70 of the control member and prevent it from pounding and wearing on its back swing in operation. Also this opening decreases the weight of the clip and provides an opportunity for access to the operating parts for 75 cleaning and the like.

In constructing the jaw control or feeler member 18, I prefer to stamp the same in a plurality of different parts from thin sheet stock, all of the parts being of identical shape, 80 and then to assemble these by forcing the bearing 19 through openings 33 which are punched in each of the parts and thus form a laminated construction. The engaging surface of the bearing tube 19 and the opening 85 33 is roughened or corrugated so as to better hold the parts assembled. By this construction, I may form the edge of the feeler member sufficiently smooth to avoid expensive machining operations. 90

My improved construction for clip is very strong and durable and the effectiveness of its operation is materially increased over the old style clip. 95

The foregoing description is directed solely 95 towards the construction illustrated, but I desire it to be understood that I reserve the privilege of resorting to all the mechanical changes to which the device is susceptible, the invention being defined and limited only 100 by the terms of the appended claims.

I claim:

1. In a tenter clip, a body portion having a fixed jaw, a pair of spaced arms extending from the body to overlie said fixed jaw, a swinging jaw pivoted in said arms to cooperate with the fixed jaw, a pivot shaft, a plurality of laterally spaced feeling fingers separately mounted upon said pivot shaft for engaging the surface of the cloth. 105

2. In a tenter clip, a body portion having a fixed jaw, a pair of spaced arms extending from the body to overlie said fixed jaw, a swinging jaw pivoted in said arms to cooperate with the fixed jaw, a control member for said swinging jaw having a plurality of laterally spaced L-shaped feeler fingers and a bearing member extending through said fingers at the juncture of the angularly-extending portion of said L, and means for pivotally mounting said bearing member in said arms. 115

3. In a tenter clip, a body portion having a fixed jaw, a pair of spaced arms extending from the body to overlie said fixed jaw, a swinging jaw pivoted in said arms to cooperate with the fixed jaw, a control member for said swinging jaw having a plurality of laterally spaced L-shaped feeler fingers and a bearing member integral therewith extending through said fingers at the juncture of the 125 130 135

laterally-extending portion of said L, and means for pivotally mounting said bearing member in said arms.

4. In a tenter clip, a body portion having a fixed jaw and forming a housing overlying the fixed jaw, a swinging jaw pivoted in the overlying portion of said housing to cooperate with the fixed jaw, a control member for said swinging jaw pivotally mounted in said housing, said housing having an opening in its back and top positioned to prevent the control member engaging therewith on its back swinging movement.

5. In a tenter clip, a control member formed of a plurality of sheet material parts and means for securing said parts side by side in assembled contacting relation.

6. In a tenter clip, a control member formed of a plurality of sheet material parts and mounting means for securing said parts side by side in assembled contacting relation.

7. In a tenter clip, a control member of laminated construction and means for pivotally mounting said control member in operating position in the clip.

8. In a tenter clip, a control member comprising a plurality of like sheet metal stampings positioned side by side to form a laminated construction, and a bearing member extending therethrough and in frictional engagement with the parts thereof to move therewith and hold them in assembled relation.

9. In a tenter clip, a control member comprising a plurality of like sheet metal stampings positioned side by side and each having an opening therein, and a tubular bearing member extending through said opening and in frictional engagement with the walls thereof to hold said stampings in assembled relation.

In testimony whereof I affix my signature.
WILLIAM A. STELLING.
